Inventor:
Eleazer Kempshall,
By his Attorney,

J. H. Richards.

UNITED STATES PATENT OFFICE.

ELEAZER KEMPSHALL, OF BOSTON, MASSACHUSETTS, ASSIGNOR TO THE KEMPSHALL MANUFACTURING COMPANY, A CORPORATION OF NEW JERSEY.

GOLF-BALL.

SPECIFICATION forming part of Letters Patent No. 699,876, dated May 13, 1902.

Application filed April 8, 1902. Serial No. 101,887. (No model.)

To all whom it may concern:

Be it known that I, ELEAZER KEMPSHALL, a citizen of the United States, residing in Boston, in the county of Suffolk and State of Massachusetts, have invented certain new and useful Improvements in Playing-Balls, of which the following is a specification.

This invention relates to playing-balls, and especially to those which are subjected to severe usage, as in the game of golf; and its object is to reduce the liability of the ball becoming lipped or cut by an implement or by striking a rock. I also aim to reduce the sensitiveness of the ball when given a light blow, as in "putting," without impairing its usefulness in driving. I also prevent undue slip of the ball when in contact with the implement.

Figure 1 is a part-sectional view of a playing-ball the elements of which are constructed and organized in accordance with my present improvements, and Fig. 2 is a similar view of a core for the ball. Fig. 3 is a view in perspective of one of the fabric-cased hemispheres of which the external structure or shell of the ball is made up. Fig. 4 is a similar view of one of the inner hemispherical sections constituting the body of the ball, and Fig. 5 is a sectional view representing one means which may be employed in the process of manufacture of my improved ball.

Before proceeding with a more detailed description it may be stated that I may employ any suitable core for the ball, to which I preferably apply in any desired way a suitable body, to which in turn I apply the fabric-cased external structure or shell of the ball, the combined elements being subjected to compression under heat to give shape to and complete the ball.

Specific reference being had to the accompanying drawings by the designating characters thereon, A, Fig. 1, represents a completed ball constructed substantially in accordance with my present improvements, the same comprising a center or core 1 of any suitable material, preferably india-rubber or other elastic substance, to which center or core I apply a body 2, Fig. 1, also of any suitable material, preferably gutta-percha or the like, and which is constructed prefer-

ably of hemispherical sections 3, Figs. 4 and 5, joined or welded together at the points *a b*. (See Fig. 5.) The said hemispherical segments may be applied to the center or core 55 in any suitable way, as by compression-dies, it being evident, of course, that I may dispense with both the center or core and the segments, if desired, and make the body of the ball of one solid spherical mass. The use of said center or core is preferred, however, in the present instance. To the outer surface of the body of the ball I apply in any suitable way a fabric-cased outer structure or shell 5, Fig. 1, which may be constituted of any preferred substance 65 or material 6, such as celluloid, capable of being softened or rendered plastic by heat, combined with a suitable woven fabric 7, attached to or partially embedded in one side or surface thereof, preferably leaving the 70 other side free for direct contact and association with the surfaces of the applied hemispherical sections 3 of the body. I preferably apply said fabric-cased outer structure or shell 5, Fig. 1, also in the form of hemispherical sections B, Fig. 3, which are placed upon the body 2 of the ball, and then the structure is subjected to compression under heat in suitable dies 8 and 9 for the purpose 75 shown in Fig. 5. While being thus compressed the materials of both the body 2 and the outer structure or shell 5 are softened by the action of the heat of the dies, and the adjacent surfaces of said elements blend and become practically united, and in this way 80 there is no liability to displacement of the outer structure or shell upon said body. The pressure of the dies also unites the outer fabric casing with the material of the said outer structure or shell more perfectly, and the adjacent faces of the hemispherical sections of 85 which the latter is made up are firmly united or welded in a manner quite apparent. The union of such faces is also such as to present no roughness or unevenness of the edges of 90 the fabric element of said hemispheres, and I thus obtain a perfectly-spherical fabric-cased playing-ball possessing all the desirable qualities of such a structure or embodiment. 95 Variations may be made without departure 100 from the spirit and scope of my invention, as is evident.

- Having described my invention, I claim—
1. A playing-ball having a cloth cover, said ball comprising a springy core and a celluloid casing with which said cover is incorporated.
  - 5 2. A playing-ball having a cloth cover, said ball comprising a sphere of gutta-percha, and a celluloid casing upon said sphere, the cloth being incorporated with said casing.
  - 10 3. A playing-ball having a cloth cover, said ball comprising a springy core, a sphere of gutta-percha inclosing said core, and a casing of celluloid upon said sphere, the cloth being incorporated with said casing.
  - 15 4. A playing-ball having a cloth cover, said ball comprising a shell of celluloid upon which said cover is applied; the cloth being incorporated with the celluloid.
  - 20 5. A playing-ball having a sectional cloth cover, said ball comprising a sphere of plastic material and a casing consisting of welded segments of celluloid each of which has incorporated therewith a section of said cloth cover.

ELEAZER KEMPSHALL.
